UNITED STATES PATENT OFFICE.

JOHN M. BENJAMIN, OF BEVERLY, MASSACHUSETTS, ASSIGNOR TO UNITED SHOE MACHINERY COMPANY, OF PATERSON, NEW JERSEY, A CORPORATION OF NEW JERSEY.

LAST-PULLING MACHINE.

1,203,571.

Specification of Letters Patent.

Patented Nov. 7, 1916.

Application filed March 10, 1915. Serial No. 13,385.

To all whom it may concern:

Be it known that I, JOHN M. BENJAMIN, a citizen of the United States, residing at Beverly, in the county of Essex and State 5 of Massachusetts, have invented certain Improvements in Last-Pulling Machines, of which the following description, in connection with the accompanying drawings, is a specification, like reference characters on the 10 drawings indicating like parts in the several figures.

This invention relates to machines for separating shoes and lasts, commonly termed last pulling machines, and the general object of the invention is to provide an improved machine of this class.

In the manufacture of boots and shoes, after the shoes have been lasted and, in the manufacture of welt shoes, after the outsoles 20 and heels have been attached and the shoes have been substantially finished, it is necessary to separate the shoes from the lasts over which the shoes have been shaped.

By reason of the fact that in the lasting 25 operation, the upper is drawn as tightly as possible over its last and secured in the closest possible conformity to the last, the operation of separating a shoe and last necessarily involves subjecting various parts of 30 the shoe to considerable strains. Consequently, it is of the utmost importance to the success of a last pulling machine that it be organized to reduce these strains to a minimum, in order to prevent injuriously straining and tearing, distorting, or otherwise 35 damaging the shoes operated upon.

By the invention set forth in the co-pending application of Benjamin F. Mayo, Serial No. 869,824, filed Nov. 2, 1914, a successful last pulling machine was provided for the first time, the success of that machine being largely due to the adequate way in which it was organized to effect the separation of a shoe and last by relative movement of the 45 shoe and last along lines of least resistance, provision being made for self accommodation of the machine parts to different conditions including different shapes of lasts and shoes and different relative positions of lasts 50 and shoes during last pulling operations.

A specific object of the present invention is to improve the machine disclosed in the above mentioned application without sacri-

ficing any of the above stated and other features and advantages characteristic of that 55 machine, to the end that a machine may be produced by the use of which the separation of shoes and lasts may be accomplished with still greater facility by an organization operating to diminish still further the shoe 60 strains incident to the last pulling operation. Accordingly, the present invention is herein shown and described as embodied in a machine of the type disclosed in said co-pending application. It is to be understood, 65 however, that the invention may have other uses, including application to last pulling machines of other types. In accordance with this object of the present invention, the machine herein shown and described as illustrating a preferred embodiment of the invention 70 is constructed and arranged to cause the shoe and last separating force exerted by the machine to be varied automatically according to variations in resistance to separation offered by the shoe and last during 75 the shoe and last separating movement. To this end, the illustrated machine includes in addition to mechanism for effecting relative movement of a shoe and last in directions to 80 separate the shoe and last completely, coacting spring auxiliary means coöperating automatically with that mechanism in the production of the shoe and last separating movement. This auxiliary means operates to reduce very greatly the last pulling strains 85 upon the shoe, particularly in the region of the throat of the vamp where the strains are especially pronounced by reason of the necessity of effecting relative passage of the 90 extreme wide part of the last through the narrow opening at the throat of the vamp, by regulating the last pulling movement automatically according to the resistance to separation offered by the shoe and last at 95 different stages in the last pulling operation and by exerting yieldingly force tending to effect relative lengthwise movement of the shoe and last in a direction to facilitate freeing the last from the shoe. The illustrated 100 construction and arrangement are such that, during the early stages of the last pulling movement when the last pulling strains upon the shoe are the greatest, the last pulling movement is automatically retarded to prevent injuriously straining the shoe while, as

105

soon as rendered permissible by the relative positions of shoe and last, the last movement is automatically accelerated.

Another object of the invention is to provide means for firmly supporting the forepart of a shoe which means will be adapted to be incorporated readily in a machine of the type disclosed in the above mentioned application. In accordance with this object of the invention, a feature of the illustrated machine consists in a novel shoe forepart support especially constructed and arranged not to interfere with necessary shoe positioning movements while coöperating with shoe clamping means to hold the shoe firmly against last pulling movement when the shoe is in operative position.

These and other objects and features of the invention including certain novel features residing in the construction and arrangement of the illustrated shoe sole engaging devices and the provision of novel shoe positioning and gaging means will be apparent from the following detailed description read in connection with the drawings and the various novel features of the invention are set forth in the appended claims.

Referring to the drawings, Figure 1 is a side elevation of an illustrative machine embodying the present invention, with portions of the machine frame broken away to show inclosed mechanism; Fig. 2 is a perspective view showing the work engaging parts of the machine in operative relation to a shoe; Fig. 3 is a top plan view of the machine; Fig. 4 is a transverse vertical section showing a shoe held in position for a last pulling operation; Fig. 5 is a longitudinal vertical section showing a shoe sole engaging device in operative relation to a shoe; and Fig. 6 is a front elevation of the shoe sole engaging device of Fig. 5, parts being broken away to show the mounting of the device.

As above stated, the machine herein shown and described for the purpose of illustrating a preferred embodiment of the present invention is a machine of the type disclosed in said co-pending application of Benjamin F. Mayo. Conveniently, and as shown, except as hereinafter fully explained and described in detail, the machine may be constructed like or substantially like the machine illustrated in said co-pending application and reference should be had to the specification and drawings of that application for detailed exposition of features and details of construction and operation not fully explained and described herein.

The illustrated machine comprises a heavy upright column designed to stand on a floor and having in its upper part a bearing sleeve 2 (Figs. 1 and 3) for a power shaft 4. The shaft 4 carries a loose pulley 6 intend-

ed to be connected to a source of power and having a clutch surface formed to be engaged by a cone clutch member 8 splined on the shaft 4. When permitted, the clutch member 8 is moved toward the right (Fig. 70 1) to close the clutch by a compression spring 10 within the hub of the clutch member 8 and held between said clutch member and a portion of the shaft bearing 2. The spring 10 is permitted to operate the clutch 75 member 8 to close the clutch upon movement of a lever 12 having a forked upper arm (Fig. 3) pivoted at 14 to the clutch member 8 and operated by a toggle 16, 18 (Fig. 1) to which is pivoted a rod 20 pivotally connected at its lower end to the rear end of a starting treadle 22. Depression of the treadle 22 raises the rod 20 and breaks the toggle 16, 18 to move the lever 12 toward the right (Fig. 1) to permit the spring 85 10 to close the clutch. The treadle 22 is normally maintained elevated at its free end by a spring 24, the rod 20 being thereby normally pulled down, thus depressing the pivotal connection of the rod 20 with the 90 toggle 16, 18 as far as permitted by a stop 26. A turn buckle 28 provides for adjustment of the rod 20.

To provide for opening the clutch automatically at the end of a machine cycle, the upper end of the lever 12 is pivoted at 30 to the rear end of a link 32 guided between fixed ears 34 upstanding from the bearing 2 in which the shaft 4 turns. The front end of the link 32 is forked to embrace the hub 100 of a cam disk 36 fixed on a cam shaft 38 carrying a fixed worm gear 40 meshing with a worm 42 fixed on the shaft 4, the construction being such that the cam shaft 38 makes one half a revolution for each 105 complete cycle of the machine. The described connection of the front end of the link 32 with the hub of the cam disk 36 is such as to allow sliding movement of the link 32 forwardly and backwardly parallel to the 110 shaft 4. On one of its side faces, the link 32 has a projection 44 the outer edge face of which projection is eccentric to the axis of the cam shaft 38 and normally located to be engaged by one or the other of rolls 115 46, 48 carried on one side of the cam disk 36, such engagement forcing the link 32 forwardly toward the left (Fig. 1) thereby moving the lever 12 in the direction to pull the clutch member 8 out of driving contact 120 with the coöperating clutch face on the continuously running pulley 6 and locking the said clutch member in inoperative position.

Upon depression of the treadle 22 and resultant breaking of the toggle 16, 18, the lower end of lever 12 is moved toward the right since the outer end of link 18 turns about a fixed pivot. In the normal positions of the parts, the cam disk 36 is at rest with either the roll 46 or the roll 48 in engage- 125 130

ment with the projecting portion 44 of link 32, the link 32 being thereby held stationary at the left hand limit of its movement, looking at Fig. 1, so that, upon depression of the 5 treadle and consequent movement of the lever 12 toward the right (Fig. 1), said lever fulcrums about its connection 30 with link 32, thereby allowing the spring 10 to snap the clutch member 8 into clutching engagement 10 with the driving pulley 6. The shafts 4 and 38 are thereupon set in motion and the roll 46 or 48 passes off the projection 44, leaving the link 32 free to slide endwise toward the right (Fig. 1). The operator is 15 expected to remove his foot from the treadle as soon as the machine is started whereupon the spring 10 restores the toggle 16, 18 to the position shown in Fig. 1, thus swinging the lower end of lever 12 toward the left (Fig. 20 1). In this movement, the lever 12 turns about its pivotal connection 14 with the clutch member 8, since the spring 10 is forcing the clutch member 8 toward the right. Such movement of the lever 12 toward the 25 left draws the link 32 toward the right and thereby locates the projection 38 in the path of the approaching roll 46 or 48. When said roll 46 or 48 engages the projection 44, the link 32 is thereby forced toward the 30 left and, inasmuch as the toggle 16, 18 holds the lower end of lever 12 against movement toward the right, movement of the link 32 toward the left causes the lever 12 to fulcrum about its connection 50 with toggle link 16, in consequence of which the clutch member 8 is pulled out of clutch engagement 35 with the pulley 6 and the machine is stopped. In the illustrated construction, this disconnection of the clutch members 40 takes place automatically at the end of a half revolution of the cam shaft 38 which occurs at the end of the complete cycle of the machine.

The above described clutch mechanism for 45 starting and stopping the machine is not claimed herein but forms the subject matter of my application for starting and stopping mechanism, filed May 29, 1915, Serial No. 31,240.

50 For holding a shoe for a last pulling operation, the illustrated machine is provided with shoe holding means comprising members for clamping the rear portion of a shoe, together with auxiliary shoe holding devices engaging the shoe sole in the region of the shank of the shoe.

For clamping the rear portion of a shoe, the illustrated machine is provided with counter and heel grippers 52, 54, comprising 55 opposed independent blocks of rubber or other suitable material arranged to engage opposite sides of the counter and heel of the shoe and mounted for movement from inoperative positions into operative engagement with the shoe. Except for differences

due to opposition, the shoe gripping members 52, 54 and associated parts are alike for the two sides of the shoe.

The counter and heel grippers 52, 54 are carried at the inner ends of stems 56, 58 70 formed by inner and outer telescoping sections between which are seated adjustable relief springs 59.

75 Preferably, and as shown, both the counter and heel gripper blocks have their work engaging faces concaved horizontally and lengthwise of a shoe (Fig. 3) and also vertically and transversely of the shoe (Fig. 4) to cause them to conform substantially both to the horizontal and to the vertical contours 80 of the sides of a shoe counter and heel.

To provide for movement of the shoe clamping members 52, 54 into operative engagement with a shoe, the stems 56, 58 are carried by frames 60 movable endwise toward and from a shoe in stationary slide-ways. The frames 60 are operated from the cam disk 36 to carry the shoe clamping members 52, 54 into and out of operative position. The cam disk 36 has in its periphery two opposed relatively short low parts or depressions, one of which is indicated at 62 (Fig. 1). A bell crank 64 fulcrumed at 66 carries on its lower arm a roll 68 (Fig. 1) which engages the periphery of 90 the cam disk 36. The upper end of the bell crank 64 engages and intermittently thrusts toward the left (Fig. 1) against the pull of return springs 70, a plunger 72 carrying a cross head 74 (Fig. 3) connected by links 100 80 to the rear arms of bell cranks 82. The bell cranks 82 are fulcrumed at 84 to fixed portions of the machine frame and their front arms are linked by adjustable bars 86 to the frames 60. Upon movement of the frames 60, effected through the above described connections with the lever 64 and cam disk 36, substantially right line movement toward and from shoe engaging position is imparted to the counter and heel 105 grippers 52, 54.

The counter and heel gripper blocks are 110 removably carried in holders 88 (Fig. 4) each of which holders is swiveled on its stem by a vertical pivot 90, a supporting plate 115 92 sustaining the grippers against sagging. The swiveled mounting of the counter and heel gripper holders renders the counter and heel grippers freely self positioning further to accommodate them to the contour of the 120 sides of a shoe counter and heel from the heel breast line rearwardly. The counter and heel grippers 52, 54 are rendered still further self accommodating to different sizes and shapes of shoes by the provision 125 of the above described springs 59 which operate to cause the said grippers to engage a shoe with adjustable spring pressure. Also, adjustment of the extent of shoe engaging movement of the grippers 52, 54 130

according to varying conditions, particularly for shoes of different widths, is provided for by the before mentioned adjustable bars 86.

- 5 In addition to the described counter and heel clamps 52, 54, the illustrated machine is provided, as above stated, with auxiliary shoe holding means coöperating with the grippers 52, 54 to hold a shoe for a last 10 pulling operation by engagement with the shoe sole on opposite sides of the sole. To this end, each gripper carrying frame 60 has an extension 94 into which is threaded an adjusting nut 96 (Fig. 5) bearing against 15 one end of a spring 98 encircling a stem 100 of a carrier 102 and seated at its other end against an outstanding annular rim on said stem 100. The front end of each carrier 102 is adapted to be dove-tailed into a holder 20 104 carrying a shoe sole engaging device 106. The shoe sole engaging devices 106 are located relatively to the counter and heel grippers 52, 54 to engage a shoe in the shank and conveniently, as indicated in Fig. 2, well 25 forward in the shank near the line of the break between the forepart and shank. In the illustrated construction each device 106 comprises a relatively thin flat blade adapted to engage a shoe in the welt crease. The 30 auxiliary shoe holding devices 106 not only coöperate with the shoe holding grippers 52, 54 in positioning a shoe and holding it positioned for a last pulling operation, but at the same time afford additional support 35 for the shoe, particularly in the region of the shank, to prevent bending the shoe sole and thus cracking or injuring the sole finish and distorting the upper.

Preferably, as shown in Fig. 1, the devices 40 106 are normally inclined at an oblique angle to the vertical to position their crease engaging blades approximately to the spring of a shoe shank. To provide for adjusting the devices 106 for lasts differing in spring, 45 each carrier 102 for a shoe sole engaging device 106 has a vertical slot entered by a roll 108 (Fig. 5) on a bolt 110 passing through a slot 112 (Fig. 3) in a stationary guide 114, the slot 112 being long enough to allow 50 tipping or swinging adjusting movement of the carrier 102 about its lengthwise axis. Preferably, in addition to the described provision for adjusting each carrier 102 about its lengthwise axis to adjust the devices 106 55 for lasts varying in spring, the blades 106 are mounted to be self positioning to a sufficient extent to accommodate them to ordinary variations in the spring of lasts to avoid the necessity of employing the described adjustment except infrequently, thus 60 effecting a substantial saving in time and labor. To this end, as shown, each blade 106 is preferably pivoted on a pivot stud 116 (Fig. 6) projecting from the associated

holder 104, the holder 104 being cut away 65 at its lower end to form a seat for the reception of an upstanding extension 118 integral with the blade 106. Preferably, the extension 118 is formed to present a substantially semi-circular periphery in sliding contact 70 with complementary shoulders indicated at 120 on the holder 104. A spring 122 held at its upper end in a slot in the holder 104 is received freely at its lower end in a slot 75 124 in the extension 118 of the device 106, the spring 122 lying in a vertically disposed tapering recess 126 formed by an extension or elongation of the recess in which the extension 118 of the device 106 is received. The spring 122 operates to maintain the 80 blade 106 normally in a central position with respect to its holder 104, and to return the said device automatically to central position after displacement. Swinging movement of each device 106 either way about its pivot 85 116 as an axis positions each blade 106 according to the spring of a particular shoe shank. A cover plate 128 secures each device 106 to its holder 104.

Further adjustment of each device 106 90 is provided for by a screw 127 and lock nut 129 (Fig. 5) by means of which the holders 104 carrying the devices 106 may be adjusted up or down in a generally vertical direction and secured in adjusted positions to 95 position the devices 106 for shoe shanks differing in height. Also, as in the case of the counter and heel grippers 52, 54, the auxiliary shoe holding devices 106 are pressed against the work under adjustable spring 100 pressure by means of the before mentioned springs 98.

To facilitate correct positioning of a shoe with relation to the shoe holding devices and to coöperate with the counter and heel grippers 52, 54 to prevent lengthwise heelward movement of the shoe, the illustrated machine is provided with a shoe back gage 130 (Fig. 2) comprising a vertically disposed plate covered by a strip of rubber or other 105 resilient or non-abrasive material and carried at the lower end of a vertical rod 132 adjustably secured to a carrier 134. The gage carrier 134 has a slotted rearward extension 136 adjustably secured to the machine frame for horizontal movement out or 110 in from or toward the machine.

Still further to facilitate correct presentation and positioning of a shoe, the illustrated machine has a shoe height gage comprising a gage member 138 for engagement 115 with the tread face of the heel of a shoe or the heel seat of a shoe bottom. The gage member 138 is carried at the lower end of a vertical rod 140 adjustably secured to the 120 gage carrier 134. Conveniently, the gage member 138 may have a considerably elongated work engaging foot, as shown in Fig. 125

2, thereby adapting it for proper engagement with heels of different styles, particularly for heels differing in pitch.

In the use of the machine, the described power driven mechanism provides for automatically and substantially simultaneously advancing the shoe holding grippers 52, 54 and the auxiliary shoe sole engaging and holding devices 106 yieldingly into operative engagement with a shoe upon movement of the cam disk 36. The described contour of the cam disk 36 operates to cause the shoe to be held securely clamped against last pulling movement until the roll 68 on the lever 64 drops into one of the depressions 62 in the periphery of the cam disk 36 at the end of a half revolution of the shaft 38, whereupon the springs 70 retract the shoe engaging devices 52, 54, 106 to the normal inoperative positions shown in Fig. 3, thereby releasing the shoe.

For engaging and holding a last and withdrawing it from its shoe while the shoe is held by the clamping devices 52, 54, 106, the illustrated machine is provided with a last support and holder comprising a spindle 142 (Fig. 1) carried on the front end of a swinging carrier 144 (Figs. 1 and 2) pivotally connected at its rear end at 145 to the upper end of one arm 146 of a bell crank fulcrumed at 148 on the upper end of a plunger 150. The other arm 152 of the said bell crank has pivoted to its front end a rod 154 passing loosely at its lower end through a stationary guide 156 and encircled by a compression spring 158. An adjusting nut 160 and check nut 162 are threaded on the rod 158 near its upper end, the spring 158 being seated between the adjusting nut 160 and the upper face of the guide 156 and the nuts 160 and 162 providing for adjusting the tension of the spring 158. The plunger 150 passes through a guide 164 and is pivotally connected at its lower end to a lever 166 (Fig. 1) fulcrumed at its rear end at 168 and normally upheld by a counter weight 169. The lever 166 is pivotally connected intermediate between its ends at 170 to a thrust bar 172 having a forked upper end 174 embracing the hub of a double armed cam 176 on the cam disk 36 which is arranged to engage a roll (shown in dotted lines, Fig. 1) projecting from the thrust bar.

In the operation of the machine, after a shoe has been presented to and clamped by the shoe engaging and holding devices 52, 54, and 106 and while the shoe is thus held, the plunger 150 is forced downwardly upon movement of the cam 176 through downward movement of the thrust bar 172 and plunger supporting lever 166. During the first part of its downward movement, the plunger 150 operates to pull down the rear end of the last spindle carrier 144, thereby tipping the

last spindle 142 from the position of Fig. 2 into holding engagement with the last thereon. Thereafter, upon continued movement of the plunger 150, the last spindle 142 operates to pull the last downwardly and lengthwise heelward until the last is completely removed from the shoe. By reason of the pivotal connections 145 and 148, the plunger 150 at all times during its descent exerts upon the last spindle a distinct and increasing pull backwardly so that, during its generally downward last movement, the last spindle is caused to exert upon the last a constant and progressively increasing pull heelward. The result is that, as the last is moved downwardly, it is also moved lengthwise relatively to the shoe as soon and as much as permitted by the relative positions of the last and shoe. During the initial stages of the last pulling movement and until the last has moved downwardly far enough to clear the counter portion of the shoe, only relatively slight lengthwise movement of the last is permitted by the shoe counter materials, so that this part of the last movement is substantially perpendicular to the plane of the shoe bottom. As soon, however, as the last has moved relatively to the shoe far enough so that the heel end of the last can clear the counter portion of the shoe, at which time the last is permitted to have a very decided lengthwise movement, the lengthwise pull exerted upon the last by the last pulling mechanism operates automatically to withdraw the last lengthwise heelward from the shoe.

During the descent of the plunger 150, the spring 158 constantly exerts force upon the last carrier 144 and last spindle 142 through the bell crank 146, 152 in a direction tending to move the last lengthwise heelward relatively to its shoe. By reason of the fact that the descent of the plunger 150 takes place against the resistance of the spring 158, the compression of the spring 158 increasing progressively as the last pulling movement proceeds, the said spring retards the last pulling movement during its early stages, when the last pulling strains upon the shoe, and particularly the strains in the region of the throat of the vamp of the shoe, are the greatest, while, as soon as the heel end of the last has moved downwardly far enough so that it can clear the shoe counter, the spring 158 imparts to the last a very decided impetus lengthwise heelward, accelerating the last movement very materially. At the same time, the lengthwise force exerted on the last by the spring 158 operates, during the early stages of the last pulling movement particularly, to facilitate freeing the wide part of the last, thereby facilitating its exit through the narrow opening at the throat of the vamp. The

described construction and arrangement provide coacting yielding auxiliary means associated with the last pulling mechanism and coöperating therewith in the production 5 of the shoe and last separating movement automatically as permitted by the shoe and last which means operates to reduce very greatly the last pulling strains upon the shoe upper, particularly in the region of 10 the throat of the vamp, by regulating the action of the last pulling mechanism automatically according to the resistance to separation offered by the shoe and last in the successive stages of each last pulling 15 operation and by facilitating the withdrawal of the last from the shoe as above explained.

In addition to the described support for the heel portion of a shoe provided by the 20 last spindle 142, and coöperating with the clamping devices 52, 54, 106 to hold a shoe against last pulling movement, the illustrated machine includes means for supporting the forepart of the shoe in opposition 25 to the last pulling movement, said means comprising a depending toe embracing stirrup 178 pivotally connected to an overhead carrier rod 180 for swinging movement relatively to said rod 180. The stirrup 178 30 comprises a shoe forepart embracing loop formed intermediate between its ends to provide a shoe upper engaging rest or support (Fig. 2). To permit adjusting movement of the stirrup 178 up or down, the rod 35 180 is secured by a split clamp 182 and thumb screw 184 to a horizontally disposed rod 186. The rod 186 is similarly secured by a split clamp 188 and thumb screw 190 to an upstanding arm of the gage carrier 40 184 to permit adjusting movement of the stirrup 178 for shoes of different lengths. The toe supporting stirrup 178 is normally positioned to support the forepart of a shoe 45 in operative relation to the shoe engaging and holding members 52, 54 and 106 while, by reason of its pivotal connection with its carrier rod 180, the stirrup 178 is arranged to be swung out of normal position by contact with a shoe to permit movement of the 50 shoe from its initial position into operative relation to said shoe engaging members. To facilitate swinging the stirrup 178 out of shoe supporting position upon such positioning movement of the shoe, the said stirrup 55 is provided with a depending tail piece 192 projecting obliquely across the path of movement of a shoe into operative position and preferably, as shown, of sufficient length to insure contact with shoes of different sizes.

The machine comes to rest with the last holding spindle 142 and its supporting and operating mechanism positioned as shown in Fig. 1, the plunger 150 being fully ele-

vated. A shoe having therein a last to be 65 pulled is presented for the operation of the machine by mounting the last on the spindle 142. The shoe is then elevated into position to be engaged and held by the shoe clamps 52, 54 and 106, for example, by the 70 operator manually swinging the last spindle carrier 144 upwardly and positioning the shoe by contact with the back gage 130 and the height gage 138, as illustrated in Fig. 2. Conveniently, to facilitate swinging the last 75 spindle and shoe upwardly into operative relation to the shoe clamping devices, the last spindle carrier may be provided with a hand hold or finger piece 194 projecting forwardly from the last spindle carrier. During 80 the manually effected upward swinging movement of the shoe from the position of Fig. 1 to the position of Fig. 2, the toe portion of the shoe engages the inner face of the tail piece 192, operating by sliding contact 85 therewith to swing the shoe forepart supporting stirrup 178 forwardly out of shoe supporting position sufficiently to permit the shoe to pass upwardly into operative relation to the shoe clamping members. After 90 the shoe has been thus located and positioned in operative relation to the shoe clamping devices, the shoe forepart supporting stirrup 178 is returned automatically by gravity to its initial and shoe supporting position, 95 as shown in Fig. 2. When the starting treadle 22 is depressed, the shoe engaging and clamping devices 52, 54 and 106 are advanced, as above described, into yielding, 100 clamping engagement with the shoe, after which, and while the shoe is thus held, the plunger 150 is forced downwardly by the cam 176 through downward movement of the thrust bar 172 and plunger supporting lever 166. As the plunger 150 descends, it 105 operates as hereinbefore described, to tip the last spindle 142 into holding engagement with the last and then to pull the last downwardly and lengthwise heelward completely out of its shoe, the spring 158 contributing to the production of the last pulling movement and lessening the last pulling strains upon the shoe by exerting yieldingly upon the last through the bell crank 146, 110 152, last spindle carrier 144 and last spindle 115 142, progressively increasing force tending to move the last lengthwise heelward relatively to its shoe, the said spring first retarding and later accelerating the last movement as permitted by the shoe and last. 120 After the last has been completely withdrawn from the shoe, the shoe clamping devices 52, 54 and 106 are withdrawn automatically, thereby releasing the shoe, and the last pulling mechanism and other parts 125 are restored to their initial positions.

Having fully explained my invention and described in what manner the same may be

embodied, what I claim as new and desire to secure by Letters Patent of the United States is:—

1. A last pulling machine having, in combination, means for holding a shoe, means for holding a last, mechanism constructed and arranged to effect relative movement of said shoe holding means and said last holding means substantially perpendicularly to the plane of the shoe bottom and lengthwise of the shoe and last to separate said shoe and last, and auxiliary means associated with said mechanism and coöperating with said mechanism in the production of said relative movement. 65
2. A last pulling machine having, in combination, means for holding a shoe, means for holding a last, mechanism for relatively moving said shoe holding means and said last holding means to effect relative movement of the shoe and last to separate said shoe and last, and auxiliary means associated with said mechanism and constructed and arranged to regulate said relative movement automatically according to the resistance to separation offered by the shoe and last at different stages in a last pulling operation. 70
3. A last pulling machine having, in combination, a shoe holder, a last holder, mechanism for relatively moving said holders to effect relative movement of a shoe and last to separate said shoe and last, and auxiliary means operating upon said mechanism to accelerate said relative movement as permitted by said shoe and last. 75
4. A last pulling machine having, in combination, a shoe holder, a last holder, mechanism for relatively moving said holders to effect relative movement of a shoe and last to separate said shoe and last, and auxiliary means operating upon said mechanism to retard said relative movement to prevent injuriously straining the shoe. 80
5. A last pulling machine having, in combination, shoe holding means, last holding means, mechanism for effecting relative movement of said shoe holding means and said last holding means in directions substantially perpendicular to the plane of the shoe bottom and lengthwise of the shoe and last to separate a shoe and last, and auxiliary means coacting with said mechanism and exerting force tending to accelerate such relative lengthwise movement of said shoe and last to facilitate their separation. 85
6. A last pulling machine having, in combination, a shoe holder, a last holding spindle, mechanism for relatively moving said holder and said spindle to effect relative movement of a last and shoe to separate said shoe and last, and auxiliary spring means operating to cause the separation of the shoe and last to be effected yieldingly. 90
7. In a last pulling machine, a last holding spindle, a carrier for said spindle, a supporting member for said carrier pivoted for swinging movement, and a spring acting on said carrier through said supporting member. 95
8. In a last pulling machine, last removing means comprising a plunger, a bell crank fulcrumed on the plunger, a carrier pivoted to one arm of the bell crank, a last holder on said carrier, and a spring acting against the other arm of the bell crank. 100
9. In a last pulling machine, shoe holding means, last holding means comprising a last spindle, a carrier for said spindle pivoted for manually effected swinging movement to position a last and shoe thereon with relation to said shoe holding means, an operating member, an intermediate member operatively connected to said operating member and said carrier, a hand hold or finger piece fixed to said carrier for effecting positioning movement of said carrier and spindle, and mechanism for operating said carrier and spindle through said operating member and said intermediate member to remove a last from a shoe. 105
10. A machine for use in the manufacture of boots and shoes having, in combination, means for clamping the rear part of a shoe, a spindle constructed and arranged for holding engagement with a last, mechanism for moving said spindle to effect movement of said last relatively to said shoe, and a shoe upper engaging stirrup coöperating with said clamping means to hold said shoe against said movement of the last. 110
11. In a machine for use in the manufacture of boots and shoes, a carrier and a stirrup depending from said carrier in position to receive and position the forepart of a shoe for the operation of the machine, said stirrup comprising a shoe forepart embracing loop formed intermediate between its ends to provide a rest for the said forepart of the shoe. 115
12. In a machine for use in the manufacture of boots and shoes, means for positioning the forepart of a shoe for the operation of the machine comprising a swinging member normally in operative position and constructed and arranged to be displaced from operative position by contact with a shoe to permit positioning movement of the shoe and thereafter to be returned automatically to operative position. 120
13. In a machine for use in the manufacture of boots and shoes, means for engaging a last and means for supporting the forepart of a shoe mounted on said last comprising an overhead carrier and a depending stirrup pivotally connected to said carrier for swinging movement relatively to the carrier into and out of operative position, said 125

stirrup comprising a loop formed intermediate between its ends to provide a rest for upholding the said forepart of the shoe.

14. In a machine for use in the manufacture of boots and shoes, an overhead carrier and a depending stirrup pivotally secured to said carrier for swinging movement relatively to the carrier, said stirrup comprising a loop formed intermediate between its ends to present a rest for the forepart of a shoe and carrying a depending tail piece projecting obliquely from said rest for sliding engagement with the shoe to swing said stirrup out of operative position to permit positioning movement of said shoe.

15. In a last pulling machine, shoe sole engaging means constructed and arranged to be self positioning to the spring of a last by swinging movement one way or the other from a central position, and spring means operating normally to hold said shoe sole engaging means yieldingly in said central position.

16. In a last pulling machine, a carrier, a holder depending from said carrier, and a shoe sole engaging member pivoted to said holder to permit said shoe sole engaging member to be self positioning to the spring of a last by swinging movement of said shoe sole engaging member relatively to said holder.

17. In a last pulling machine, a holder, a pivot stud projecting from said holder, a shoe sole engaging member having an extension by which said member is pivoted on said stud for swinging movement of said member according to the spring of a last, and a spring normally centering said member with respect to said holder.

18. In a last pulling machine, a holder, a leaf spring fixed at one end to said holder, and a shoe sole engaging device pivoted to said holder for swinging movement relatively to the holder and slotted to receive freely the other end of said spring, said spring operating normally to center said device relatively to its holder and to return said device automatically to central position after displacement.

19. A last pulling machine having, in combination, means for holding a last, means for holding a shoe, means constructed and arranged to facilitate positioning and locating the shoe in operative relation to said shoe holding means comprising a gage member for engagement with the tread face of the heel of said shoe and having a relatively long shoe heel engaging foot to adapt said gage member without adjustment for shoes having heels differing in pitch, and mechanism for relatively moving said last holding means and said shoe holding means to separate a shoe and last.

20. A last pulling machine having, in

combination, means for holding a last, 65 means for holding a shoe, a shoe height gage having a relatively long shoe engaging face to facilitate initially locating and positioning said shoe in respect to said shoe holding means, and mechanism for relatively moving said last holding means and said shoe holding means to separate a shoe and last.

21. A last pulling machine having, in combination, shoe holding means, last holding means, and mechanism for relatively moving said shoe holding means and said last holding means to separate a shoe and last constructed and arranged to cause the shoe and last separating force exerted by said mechanism to be varied automatically according to variations in resistance to separation offered by the shoe and last during the shoe and last separating movement.

22. A last pulling machine having, in combination, shoe holding means, last holding means, and mechanism for relatively moving said shoe holding means and said last holding means to separate a shoe and last constructed and arranged to cause the shoe and last separating movement to be retarded or accelerated automatically according to variations in resistance to separation offered by the shoe and last at different stages in the last and shoe separating movement. 95

23. A last pulling machine having, in combination, means for holding a shoe, means for holding a last, mechanism constructed and arranged to effect relative movement of said shoe and last holding means to separate the shoe and last including lengthwise relative movement of the shoe and last after the shoe counter and last heel clear each other, and means constructed and arranged to accelerate said lengthwise separating movement between said shoe and last. 100

24. A last pulling machine having, in combination, means for holding a shoe, means for holding a last, mechanism constructed and arranged to effect relative movement of said shoe and last holding means to separate completely the shoe and last including lengthwise relative movement of the shoe and last after the shoe counter and last heel clear each other, and means constructed and arranged to accelerate said lengthwise separating movement between said shoe and last. 110

25. A last pulling machine having, in combination, means for holding a shoe, means for holding a last, mechanism constructed and arranged to effect relative movement of said shoe and last holding means to separate the last and shoe including relative lengthwise movement of the shoe and last after the shoe counter and last heel clear each other, and spring means co-operating 125

with said mechanism and constructed and arranged to accelerate said lengthwise separating movement between said shoe and last.

5 26. A last pulling machine having, in combination, a last holder, a shoe holder, a shoe back gage, a shoe height gage, a unitary holder for said gages, said gages being arranged for adjustment to position shoes of
10 different dimensions in operative relation to

said shoe holder and mechanism for relatively moving said last holder and said shoe holder to separate a shoe and last.

In testimony whereof I have signed my name to this specification in the presence 15 of two subscribing witnesses.

JOHN M. BENJAMIN.
